[57] CLAIM

The ornamental design for a disk cutter, as shown and described.

DESCRIPTION

FIG. 1 is a front, top and right side perspective view of my ornamental design for a disk cutter;

FIG. 2 is a front view of the disk cutter of FIG. 1;

FIG. 3 is a rear view of the disk cutter of FIG. 1;

FIG. 4 is a plan view of the disk cutter of FIG. 1;

FIG. 5 is a bottom view of the disk cutter of FIG. 1;

FIG. 6 is a right side view of the disk cutter of FIG. 1;

FIG. 7 is a left side view of the disk cutter of FIG. 1;

FIG. 8 is a front, top and right side perspective view of the disk cutter of FIG. 1 showing a state in which a lock

mean is released; and,

FIG. 9 is a front, top and right side perspective view of the disk cutter of FIG. 1 showing a state in which a sheet of paper is cut by the disk cutter.

The broken line showing of a sheet of paper is for illustrative purposes only and forms no part of the claimed design.

FIG. 1

FIG. 2

FIG. 3

FIG. 4

FIG. 5

FIG. 6

FIG. 7

FIG. 9
